FLY SWATTER

Leo Osterkamp, Cheviot, Ohio

Application August 11, 1933, Serial No. 684,736

1 Claim. (Cl. 43—137)

The present invention relates to new and useful improvements in fly swatters of the type including a wire handle and a flexible rubber striking sheet or body, and has for an important object to provide, in a manner as hereinafter set forth, a swatter of this character embodying novel means for mounting the rubber body on the handle.

Other objects of the invention are to provide a fly swatter which will be comparatively simple in construction, strong, durable, highly efficient and reliable in use and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:—

Figure 1 is a view in top plan of a fly swatter constructed in accordance with the present invention.

Figure 2 is a view in bottom plan of one end portion of the device.

Figure 3 is a view in side elevation of that portion of the device shown in Figure 2.

Figure 4 is a sectional view, taken substantially on the line 4—4 of Figure 1.

Figure 5 is a detail view in elevation of the frame upon which the flexible rubber body is mounted.

Referring now to the drawing in detail, it will be seen that one embodiment of the invention comprises a handle which is designated generally by the reference numeral 1, said handle being formed from a single piece of suitable wire bent upon itself in a manner to provide an elongated loop 2, and a pair of parallel side abutting legs 3. The legs 3 are welded together at space points, as at 4. At their outer ends, the legs 3 are bent to provide, in conjunction with each other, a substantially triangular frame 5, said outer ends of the legs abutting each other and being soldered or welded together, as at 6 (see Figure 5).

The reference numeral 7 designates a flexible body of rubber in sheet form which is mounted on the substantially triangular frame 5 through the medium of integral flaps 8. The flaps 8 are folded diagonally on the upper portion of the rubber body 7 over the frame 5 and secured in any suitable manner, as by vulcanizing or by an adhesive, to said body 7 below the frame 5 and also within said frame 5. Each flap 8 extends from the upper part of a side edge of the body, before the flap is folded, with its upper edge forming a continuation of the upper edge of the body 7 and

its other edge sloping downwardly and inwardly from its upper edge to the side edge of the body. The lower edges of the flaps 8 are inclined substantially from the body 7 to the free ends of said flaps and merge with the upper edges thereof. It will thus be seen that when the flaps 8 are folded on diagonal lines over the substantially triangular frame 5, the upper edges thereof extend in parallel abutting engagement with each other along the longitudinal center of the body 7 and the inclined lower edges of said flaps converge toward the free end of said body 7 in a point, as illustrated to advantage in Figure 1 of the drawing. The reference numeral 9 designates a rubber reinforcing strap which extends between the flaps 8 and which is vulcanized thereto within the frame 5. It will thus be seen that the flaps 8 constitute means for supporting and stiffening the intermediate portion of the rubber body 7 while leaving the side and free end portions of said rubber body free and comparatively flexible

It is believed that the many advantages of a fly swatter constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

A fly swatter comprising a handle formed of wire and having a substantially triangular shaped frame formed by the wire at one end thereof, an elongated rubber sheet having one end rounded and its other end straight, a pair of flaps formed with the side edges of the sheet at the flat end thereof, each flap having a straight upper edge forming a continuation of the edge of said flat end and an inclined edge extending from the straight edge of the flap to the side edge of the sheet, the corners of said flat end of the sheet being folded over the frame with their adjacent edges abutting and the flaps extending from said folded corners over portions of one face of the sheet with their straight edges abutting at the longitudinal center of the sheet and their inclined edges converging from the side edges of the sheet to a point at the longitudinal center of the sheet and spaced from the rounded end of the sheet, said folded corners and the flaps being fastened to the sheet by vulcanizing, and a strip of rubber extending across the folded corner portions and located on those portions of the corner parts which cover the triangular frame.
